UNITED STATES PATENT OFFICE.

THOMAS S. SPIVEY, OF CINCINNATI, OHIO, ASSIGNOR TO THE AMERICAN BANKER'S SAFETY COMPANY, OF WILMINGTON, DELAWARE, A CORPORATION OF DELAWARE.

BURGLAR-PROOF SAFE.

1,214,091.

Specification of Letters Patent.

Patented Jan. 30, 1917.

Application filed February 25, 1913. Serial No. 750,650.

To all whom it may concern:

Be it known that I, THOMAS S. SPIVEY, a citizen of the United States of America, and a resident of Cincinnati, in the county of 5 Hamilton and State of Ohio, have invented a certain new and useful Improvement in Burglar-Proof Safes, of which the following is a specification.

This invention relates to burglar-proof 10 safes and vaults and, more particularly, to the peculiar structure thereof in which the locking-bolts are not affected when a high-power explosive is discharged in the door-jamb crevice where safe-blowers usually 15 work to get at the interior of the safe.

The main object of the invention is to 20 provide a safe, which, when locked, is secure against malicious opening thereof by means of high explosives, there being ample 25 means provided in its construction for the outward escape of the force of said explosives, which means will readily take the shock and duly relieve the high-pressure thereof by giving way under less pressure or 30 force than that required to break or release the locking-bolts.

A further object is to so construct the door 35 as to protect the locking-bolts as much as possible by placing them out of alignment with the customary exposed door-jamb crevice. This feature is accomplished by providing a round door that has on its outer face lateral wings or plates that extend in opposite directions and with one of such extensions pivotally-connected to the fore-wall 40 of the safe for hinging said door thereto.

In the accompanying sheet of drawings, Figure 1 is a horizontal cross-section taken 45 through the front portion of a safe that is constructed according to my invention herein; Fig. 2, a front elevation of the safe; and Fig. 3, a rear elevation of the improved round safe-door and its lateral-extensions.

1 represents the safe-body having in its 50 fore-wall a circular man-hole, and 2 the middle or body portion of the closing-door.

The body 2 has an inner circular-portion that forms the door proper and is somewhat tapered to engage the correspondingly tapered and stepped jamb of the man-hole. Said body 2 has an integral laterally-extended portion 5 at opposite sides thereof that considerably overlap said circular-portion and greatly beyond the man-hole, ap-

proaching the side edges of the fore-wall, as shown in both Figs. 1 and 2. It is in these lateral-extensions 5 that I preferably provide a number of horizontal, tapered openings or outwardly-expanding vent-passages that are weakly filled or plugged with a soft 60 or fragile material 6 such as lead, plaster, wax, or the like. These tapered openings preferably communicate with a common recess or countersink 7, as shown in Figs. 1 and 3, on the inner faces of both of the lateral-extensions 5. Each of the countersinks 7 forms a common communicating-chamber at each vertical side of the door 3, in the said lateral-extensions 5 thereof, for the said 65 tapered openings or vent-passages and al- 70 low for a uniform distribution of any explosives that may possibly be surreptitiously inserted or forced beneath the said lateral-extensions 5, and thereby distributes the 75 high pressure or heavy shock of the explosion to all of the said weakly filled or plugged openings or vent-passages. If desired, however, each side-chamber 7 may be further filled with an absorbent material 75 that is adapted to readily take up the explosive and thereby somewhat further weaken or reduce its exploding force, or altogether destroy its fracturing, rupturing, or bursting power.

The locking-bolts 8 are provided in the 80 inner circular-portion 3, that forms the door proper, in a suitable manner and are duly connected to a time-lock mechanism 9. Besides, I prefer to mount a permutation or combination day-lock device 10 on the outer 85 laterally-extending portion 5 (to the left) of the front of the door, and it has suitable bolts 10', as shown dotted in Fig. 2, and, also, in plan in Fig. 1. The day-lock 10 materially adds to the resisting-strength of the 90 safe and renders it somewhat difficult to open the door, especially in the said lateral left-extension 5 thereof.

In operation, the entire door structure is 95 swung outwardly from closed position and vice versa on the forked arm 11 that is hinged at 12 to the safe-body and it is, also, pivotally-connected at 13 to the outer face of the middle or body portion 2.

It is obvious that the door, constructed 100 as herein shown, will prove an invaluable one in the art of safe building, it rendering the safe quite secure against surreptitious

opening by the use of high explosives in the covered and hidden door-jamb thereof. In the event an explosive is placed beneath the lateral left-extension 5 adjacent the day-lock 10, or near the hinges 12, beneath the lateral right-extension 5, where it would be most often and likely applied, it would immediately expand or spread into the common chamber 7 adjacent the said day-lock, 10 or the said hinges, respectively, or both, where it would be widely distributed or dissipated throughout the said chambers 7 along either or both of the lateral-exten- 15 sions 5 of the door within their overlapping surfaces. Upon the ignition of the explosive the weak or fragile fillings or plugs 6 in the tapered openings or vent-passages will instantly give way and escape outwardly before the locking-bolts 8 can possibly be affected or break and thus render the use of any explosives of practically no avail in breaking into the safe, constructed as herein, due mainly, too, to the impossibility of confining the said explosives in 20 the air-tight chambers 7 beneath the laterally-extending portions 5 of the door.

The fact that the inner circular or round portion 3 of the door proper, wherein the main locking-bolts 8 are located, is entirely concealed and protected by means of the laterally-extended portions 5, makes it quite plain that the safe is rendered still more effective and secure against surreptitious bursting or destruction by the ignition of explosives therein.

The customary eccentric 14 and its manipulating lever or handle 15 are mounted on the hanger of the door so that the center of the latter may be duly placed under the pressure of the said eccentric when the door structure is closed.

Copies of this patent may be obtained for five cents each, by addressing the "Commissioner of Patents, Washington, D C."

I claim:—

1. The combination of a hollow safe-body having a circular man-hole in its fore-wall, a circular closing-door for the said man-hole and extending outwardly beyond the face of said fore-wall, and opposite lateral-extensions on the said outwardly-extending part of the circular door adapted to laterally-overlap the said man-hole adjacent 50 the point of co-action of the circular door and its circular man-hole.

2. A burglar-proof safe comprising a hollow body-portion having a circular man-hole, a circular closing-door for the man-hole, oppositely-disposed lateral-extensions on the outer face of said circular door each having an expanding-chamber beneath it and overlapping said man-hole, horizontal vent outlets or passages provided in the 55 said lateral-extensions and leading from said expanding-chambers to their outer faces, fragile or easily dislodged plugs inserted in said vent outlets or passages and adapted to receive and offset the high pressure of an explosive when fired within said lateral-extensions.

3. A safe comprising a body-portion having a suitable man-hole, a door adapted to properly engage said man-hole and having oppositely-disposed lateral-extensions, and horizontal vent outlets or passages provided in said oppositely-disposed lateral-extensions and expanding outwardly from the inner face of said extensions to the outer face thereof and forming a ready escape for any explosive fired beneath the said lateral-extensions.

THOMAS S. SPIVEY.
